UNITED STATES PATENT OFFICE

OSWALD C. BREWSTER AND WILLIAM M. PERRY, OF CASPER, WYOMING, ASSIGNEES TO
STANDARD OIL COMPANY, OF WHITING, INDIANA, A CORPORATION OF INDIANA

APPARATUS FOR TREATING HYDROCARBON OILS

Application filed March 22, 1928. Serial No. 263,766.

The present invention relates to improvements in apparatus for treating hydrocarbon oils, and will be fully understood from the following description, illustrated by the accompanying drawing, in which apparatus for carrying the invention into effect is diagrammatically illustrated.

The processes described herein are claimed in our co-pending application Serial No. 19 263,676 now U. S. Patent 1,830,925.

Referring more particularly to the drawing, A indicates a still in which the oxidizing operation is carried on; B indicates a pipe still; and C, a flash drum.

15 The still A is divided by partition 1 into compartment 2 and compartment 3, and the two compartments communicate with each other through the overflow pipe 4 with which the partition 1 is provided. By means of 20 the overflow pipe 4, which projects upwardly into chamber 3, a body of liquid may be held in the bottom of compartment 3. Compartment 2 is provided with a draw-off pipe 5, a perforated pipe 6 through which air or 25 other oxygen-containing gas may be introduced into the still, and a pipe coil 7 located exteriorly to the still and communicating therewith through pipes 8 and 9. Pipes 8 and 9 are each equipped with valves by which 30 communication with the still may be cut off. A pump 10 may be employed to circulate oil from the compartment 2 through pipe 8 and the coil 7 and back into the still through pipe 9.

35 Compartment 3 is equipped with baffles 11 which are preferably inclined downwardly so that the fresh oil which is introduced near the top of the chamber through pipe 12 may be caused to follow a zigzag path through 40 the length of the compartment. Vapors are drawn off through vapor line 13 and condensed in the condenser 14 from which the condensate flows into the receiver 15. The receiver is provided with a gas release line 16 45 and a liquid draw-off 17.

Both compartments of the still A are equipped with man-holes 18 which are closed by plates 19. Through the two man-holes, 50 the still may be cleaned when desired. Still A is preferably lagged.

The pipe still B communicates with the lower portion of compartment 3 through pipe line 20. Pipe 20 is provided with a valve 21 and a pump 22 which may be employed to force material withdrawn from compartment 55 3 through the pipe still and into the flash drum C. A steam line 23 joins pipe 20. It is preferred, however, to introduce steam at an intermediate point in pipe still B.

The flash drum C communicates with the pipe still B through pipe line 24. The drum is equipped with a spreader-cone 25 and a vapor line 26. The vapors may be drawn off through the vapor line 26 and condenser 27, and the condensate recovered in the receiver drum 28, which is equipped with gas release line 29 and liquid draw-off line 30. The flash drum C is also equipped with a residuum draw-off line 31 through which unvaporized material from the bottom of the flash drum 70 may be returned to compartment 2. The draw-off line is provided with a valve 32.

In the operation of the process, feed stock enters compartment 3 of the still A through line 12 and after filling the bottom portion of the compartment, overflows into compartment 2, the valve 21 in line 20 preferably being closed. When the compartment 2 has been filled to the point at which pump 10 may take suction through line 8, the oil is circulated through the heating coil 7 until the oil has been brought to a suitable temperature, say 600 to 650° F. or higher, at which oxidation will begin on the supply of air to the still. When the oil in the still has reached a suitable temperature, air is supplied through the line 6 in such volume as to maintain the desired temperature in the still. Circulation of the oil through the heating 75 coil 7 may then be discontinued. It is preferred to supply fresh oil continuously through pipe 12 so that the descending stream of oil which follows a zig-zag course along the baffles 11 makes contact with the vapors 80 that are generated in compartment 2 and pass into compartment 3 through the overflow line 4.

The fresh oil is thus stripped of its lightest ends which, together with the lighter fractions of the vapors from compartment 2, pass 100

up through vapor line 13, are condensed in condenser 14 and recovered in receiver 15. The heavier fractions of the vapors from compartment 2 are condensed and returned 5 with the stripped feed stock to the pool in the bottom of compartment 3. From the body of oil thus formed, a stream of oil is pumped through pipe still B in which the temperature of the oil is raised to any desired 10 high temperature as, for example, about 800° F., to produce a gas oil distillate. Steam may be introduced into the oil from line 23 just before it enters the pipe still. The highly heated oil and steam, after leaving the pipe still B, pass through line 24 and are discharged preferably upon a spreader-cone 25. Vapors generated in the flash drum pass through vapor line 26, are condensed in coils 27 and recovered in receiver 28. The 15 residuum is drawn off through line 31 and returned to compartment 2 where it is subjected to the oxidation operation. Material in the bottom of compartment 2 may be withdrawn continuously or intermittently 20 through the valve controlled residuum line 5. If desired, the valve 21 in line 20 may be kept closed and the operation carried on without using the pipe still and flash drum. In this method of operation the excess of 25 the stripped feed stock and condensed heavier fractions of the vapors, which form the pool in the bottom of compartment 3, may pass into the oxidizing chamber 2 through the overflow pipe 4. The return line 31 from the flash drum is 30 preferably lagged so that the material returned therefrom to compartment 2 may retain as much of its heat as possible. If the oil is raised to high temperatures in the pipe still and the hot unvaporized portions returned directly in a lagged conduit to the oxidation chamber, the added heat assists materially in keeping the oil in compartment 35 2 at the temperature at which the oxidizing operation may be carried on.

The process is particularly useful in running to coke certain refractory stocks, such as the black oils of Wyoming. It is well known, 40 that in the distillation of such stocks, the gas oil cut obtained is dirty and unsatisfactory as charging stock for a pressure still, since the oxidation carries by entrainment large amounts of coky material into the vapor. In 45 the operation of the process herein disclosed, a charging stock for pressure stills is obtained that is quite satisfactory. The coky material is trapped by the fresh feed in compartment 3 along with the heavier gas oil fractions 50 which are condensed. Also, on continuous distillation with steam in pipe still B the gas oil is redistilled and recovered as clean distillate from C, while the coky material remains in the residue and is recycled to the 55 oxidizing chamber 2. The operation is pref-

erably continued until compartment 2 is full of coke.

It is not intended that the details of the process, as above set forth, shall be regarded as limitations upon the scope of the invention 70 except in so far as included in the accompanying claims.

We claim:

1. In apparatus for treating hydrocarbon oils and involving treating the heavy residues with oxygen, a chamber, means for passing oil to said chamber and permitting escape of vapors therefrom, means for heating the oil to a temperature at which oxidation occurs in the presence of an oxidizing gas, means for supplying an oxidizing gas in said chamber, a second chamber, means for introducing fresh oil into the second chamber, means for contacting therein with fresh oil the vapors from the first mentioned chamber, thereby condensing the heavier portions of said vapors, a pipe still, means for passing said condensed material and fresh oil from the second chamber through said pipe still, a flash drum, means for supplying thereto the oil from said pipe still, means for removing vapors from said flash drum, and means for returning the unvaporized material from said flash drum directly to said first mentioned chamber. 100

2. In apparatus for treating hydrocarbon oils and involving treating the heavy residues with oxygen, a chamber, means for passing oil to said chamber and permitting escape of vapors therefrom, means for heating the oil to a temperature at which oxidation occurs in the presence of an oxidizing gas, means for supplying an oxidizing gas to said chamber, a second chamber, means in said second chamber for contacting fresh oil with the vapors from said first chamber, means for passing the unvaporized portion of said fresh oil through a pipe still, means for introducing steam into the oil, a flash drum, means for conducting said unvaporized oil and said steam from said pipe still to said flash drum, means for withdrawing vapors from said flash drum, and means for returning the unvaporized material from said flash drum directly to said first chamber. 110

3. In apparatus for treating hydrocarbon oils and involving treating the heavy residues with oxygen, a still comprising upper and lower chambers separated by a partition, means for supplying oil in one direction and vapors in the other direction to one of the chambers from the other, means for raising the temperature of the oil to a temperature at which oxidation occurs in the presence of an oxidizing gas, means for supplying an oxidizing gas to the lower chamber, means for introducing fresh oil into the upper chamber, means for contacting vapors passing through said first mentioned means 120 125 130

into the upper chamber with said fresh oil, means for maintaining a pool of oil in said second chamber, means for passing a stream of oil from said pool through a pipe still, a 5 flash drum, means for supplying oil from said pipe still to said flash drum, means for withdrawing vapors from said flash drum, and means for returning the unvaporized material in said flash drum to said lower 10 chamber.

4. In apparatus for treating hydrocarbon oils and involving treating the heavy residues with oxygen, a still comprising a first chamber and a second chamber separated by 15 a partition, an open overflow pipe extending into said second chamber for maintaining therein a pool of oil and permitting passage of vapors thereto from the first chamber, means for supplying fresh oil to said 20 second chamber so that oil from said pool may overflow into said first chamber, means for heating the oil in said first chamber to a temperature at which oxidation occurs in the presence of an oxidizing gas, means for 25 supplying an oxidizing gas to said first chamber, means for contacting vapors with said fresh oil in said second chamber, means for passing a stream of oil from said pool through a pipe still, a flash drum, means for 30 passing oil from said pipe still into said flash drum, means for removing vapors from said flash drum, and means for returning the unvaporized material in said flash drum to said first chamber.

5. In apparatus for treating hydrocarbon oils and involving treating the heavy residues with oxygen, a still comprising a first chamber and a second chamber, separated by a partition, overflow means for supplying oil 40 to said first chamber, said means serving also to maintain a body of oil in said second chamber, means for heating the oil in the first chamber, means for introducing fresh oil into said second chamber, means for contacting therein the vapors passing through 45 said overflow means from said first chamber with the fresh oil in said second chamber, means for withdrawing oil from the second chamber, means for introducing steam into 50 the withdrawn oil, means for passing said oil and steam through a pipe still and a flash drum, means for removing the vapors evolved in said flash drum, and means for returning the unvaporized portions of the oil 55 to said first chamber.

6. In apparatus for treating hydrocarbon oils and involving treating the heavy residues with oxygen, an oxidizing chamber, means for passing oil to said chamber and permitting escape of vapors therefrom, means for heating the oil in said oxidizing chamber to a temperature at which oxidation occurs in the presence of an oxidizing gas, means for supplying an oxidizing gas to said oil, a reflux chamber, means for supplying fresh oil 60

thereto, means for contacting the vapors from said oxidizing chamber with said fresh oil in said reflux chamber, means for maintaining a pool of oil in said reflux chamber, a pipe still, a flash drum, means for passing oil from said pool through said pipe still and into said flash drum, means for removing the vapors from said flash drum, and means for returning the unvaporized material therein to said oxidizing chamber. 75

7. In apparatus for treating hydrocarbon oils and involving treating the heavy residues with oxygen, an oxidizing chamber, means for passing oil to said chamber and permitting escape of vapors therefrom, means for heating said oil to a temperature at which oxidation occurs in the presence of an oxidizing gas, means for supplying an oxidizing gas in said oil, a second chamber, means for supplying fresh oil therein, means for contacting vapors from said oxidizing chamber with fresh oil in said second chamber whereby said oil is stripped of some of its light fractions, a pipe still, means for passing said stripped oil through said pipe still, means for introducing steam into said stripped oil being passed through the pipe still, a flash drum, means for discharging oil from said pipe still into said flash drum, means for removing the vapors therefrom, and means for returning the unvaporized portions directly to said oxidizing chamber. 90

8. In apparatus for treating hydrocarbon oils and involving treating the heavy residue with oxygen, a still comprising two chambers separated by a partition, an open overflow pipe between the chambers and extending into the upper chamber so as to maintain therein a body of oil and to permit vapors to pass therethrough, means for introducing oil into the upper chamber so that it may overflow through the overflow pipe into the lower chamber, means for withdrawing a portion of the body of oil in said upper chamber, means for heating the withdrawn portion of the oil, means for flashing the withdrawn portion of the oil, means for heating the oil in said lower chamber until a temperature is reached at which oxidation will take place in the presence of an oxidizing gas, means for supplying an oxidizing gas to said lower chamber, means for contacting vapors from said lower chamber passing through said overflow pipe with oil in said upper chamber, thereby condensing the 110 heavier portions of said vapors, means for removing the lighter portions from said upper chamber and means for removing residuum from said lower chamber. 115

9. In apparatus for treating hydrocarbon oils and involving treating the heavy residue with oxygen, a still comprising two chambers separated by a partition, an open overflow pipe between the chambers and extending into the upper chamber so as to maintain 120

therein a body of oil and to permit vapors to pass therethrough, means for introducing oil into the upper chamber so that it may overflow through the overflow pipe into the lower 5 chamber, means for withdrawing a portion of the body of oil in said upper chamber, means for heating the withdrawn portion of the oil, means for flashing the withdrawn portion of the oil, means for heating the oil 10 in said lower chamber until a temperature is reached at which oxidation will take place in the presence of an oxidizing gas, means for supplying an oxidizing gas to said lower chamber, means for contacting vapors from 15 said lower chamber passing through said overflow pipe with oil in said upper chamber, thereby condensing the heavier portions of said vapors, means for removing the lighter portions from said upper chamber, 20 means for removing residuum from said lower chamber and means for returning the unvaporized portions of the oil from the flashing means to the lower chamber.

25 In witness whereof we have hereunto set our hands this 15th day of March, 1928.

OSWALD C. BREWSTER.
WILLIAM M. PERRY.
